(57) **CLAIM**

The ornamental design for display screen or portion thereof with animated graphical user interface, substantially as shown and described.

DESCRIPTION

FIG. 1 is a front view of the first image of a display screen or portion thereof with animated graphical user interface showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof; and,

FIG. 9 is a ninth image thereof.

The outermost broken lines illustrate a portion of a display screen or portion thereof. The broken line showing of the headphones and the electronic device, shown within the circles, illustrates portions of the animated graphical user interface. None of the broken lines form part of the claimed design.

The appearance of the animated image sequentially transitions between the images shown in FIGS. 1-9. The process or period in which one image transitions to another forms no part of the claimed design.
